SELDEN SNOW, OF SOMERS, CONNECTICUT.

Letters Patent No. 88,921, dated April 13, 1869.

IMPROVEMENT IN FOLDING MILKING-SEAT.

The Schedule referred to in these Letters Patent and making part of the same.

To all whom it may concern:

Be it known that I, SELDEN SNOW, of Somers, in the county of Tolland, and State of Connecticut, have invented a new and improved Folding Milking-Seat; and I do hereby declare that the following is a full, clear, and exact description thereof, which will enable those skilled in the art to make and use the same, reference being had to the accompanying drawings, forming part of this specification.

This invention relates to a useful improvement in seats used in milking cows, whereby they are rendered much more convenient than the seats, or stools commonly used for that purpose.

The invention consists in making a bench, or seat, supported on cross-legs, with a shelf in combination therewith, arranged as hereinafter described.

Figure 1 represents a side view of the seat, extended, as when in use, showing the shelf upon which the milking-pail is placed.

Figure 2 shows the same, partially folded up.

Similar letters of reference indicate corresponding parts.

A represents the seat;

B is the shelf; and

C is the stand by which they are supported.

The seat is hinged to the stand, as seen at d, and the shelf is hinged to the stand, as seen at E.

The stand C is made of two crosses, and is similar in construction to an ordinary saw-buck.

When extended, or in use, as represented in fig. 1,

the seat rests upon the upper ends of the stands, as seen at f.

G is a rod which is attached by staples to the under side of the seat A, and to the shelf, for affording additional support to the shelf.

h is a rod which extends from one cross of the stand to the other, under the shelf, upon which the shelf rests, as seen in the drawing.

I represents a handle attached to the seat A, by which the article is hung up or carried.

J is a button, which fastens the shelf down on to the rod h, when the shelf is in use.

By securing the parts together in this manner, (by jointed connections,) it will be seen that the whole may be folded together so as to occupy a very small space, as seen in fig. 2.

The advantages of this arrangement are that a clean place is provided for the milking-pail, and, secondly, a clean and proper place is found for the milking-stool, or seat, as it may be folded and hung up out of the filth, and out of the way.

I claim as new, and desire to secure by Letters Patent—

A milking-seat, provided with a shelf, arranged in combination with the stand, or support, so as to fold up, substantially as shown and described.

SELDEN SNOW.
